UNITED STATES PATENT OFFICE.

HORACE M. WOOLLEY, JR., OF ALAMEDA, CALIFORNIA.

REINFORCING-BAR SUPPORT.

Application filed September 10, 1924. Serial No. 736,873.

To all whom it may concern:

Be it known that I, HORACE M. WOOLLEY, Jr., a citizen of the United States, residing at Alameda, county of Alameda, and State of California, have invented new and useful Improvements in Reinforcing-Bar Supports, of which the following is a specification.

This invention relates to a reinforcing bar support to be used in the construction of reinforced concrete buildings.

In constructing concrete buildings and the like, it is common practice to reinforce the beams, floor slabs, walls, columns, etc., with long iron bars or rods, etc. The reinforcing iron is placed in position after the forms have been completed or during the construction or erection of the same, and considerable care must be taken to insure a proper spacing between the forms and the reinforcing rods and between the rods themselves, so that they will be properly embedded and bonded in the concrete, when this is poured and set. To insure such spacing short sections of the reinforcing material are often interposed between the rods and the forms and tied with wire; small blocks of concrete are employed in the same way; the reinforcing rods are in some instances suspended in the forms by means of wires, and in other instances specifically constructed bar supports are employed. In other words a contractor will usually resort to whatever material happens to be most plentiful or convenient at the time. This results in waste of materials, inferior construction, and in loss of time, as far as the workers are concerned, and produces anything but economy and efficiency. Furthermore, by resorting to the use of make-shift methods and materials, it often happens that the reinforcing rods are not sufficiently or rigidly secured and as such become displaced during the pouring and tamping of the concrete, thereby causing improper bonding and weakening of the structure.

The object of the present invention is to overcome the objections referred to by providing a reinforcing bar support which may be used in beams, floor slabs, and in fact wherever reinforcing material is required; a bar support which is substantial; a bar support which is capable of receiving and supporting rods of any size and diameter; a bar support which permits any desired spacing between the rods; a bar

support which will positively secure the rods and prevent displacement when pouring or tamping the concrete; and further, a bar support which will save time and labor by eliminating the expense and delay of tying the bars with wire, and which may be economically manufactured.

One form which my invention may assume is exemplified in the following description and illustrated in the accompanying drawings, in which—

Fig. 1 is a front view of the bar support showing two reinforcing rods supported thereby.

Fig. 2 is a cross-section on line 2—2 of Fig. 1.

Fig. 3 is a perspective view of a bar support bent into a Z-shape.

Fig. 4 is a perspective view of the supporting bar showing it corrugated or angularly bent throughout its length to permit it to be self-supporting when placed edge-wise.

Fig. 5 is a section of a concrete floor showing the position of the reinforcing rods and reinforcing rod supports.

Referring to the drawings in detail, and particularly to Figs. 1 and 2, A indicates in general the reinforcing rod support forming the subject matter of the present application. The support is constructed of strap iron or fairly heavy sheet metal and is produced in strip form of suitable lengths. One edge is cut by a die or any other suitable means to form a series of alternate teeth and spaces as indicated at 2 and 3. The teeth are preferably thin, as a great amount of rigidity is not required. In fact it is desirable that they should be fairly easily crushed or displaced as crushing or displacement of the teeth is resorted to when the reinforcing rods are placed in position.

The strips or supports indicated at A may be cut into suitable lengths for use and the ends may be bent, as indicated at 4 in Fig. 3, to form a Z-bar shape, the ends being bent for the purpose of rendering the strip or bar self-supporting when placed on edge. The strip may also be corrugated throughout its length, or sections thereof may be angularly bent as shown in Fig. 4. In other words the bars or strips may be bent into numerous shapes to cause them to be self-supporting; or in other words to assume a vertical or edgewise position when so desired.

The actual use of the reenforcing bar support is perhaps best illustrated in Figs. 1, 2 and 5. In Fig. 5 a section of a concrete floor is illustrated. In this view B indicates the floor slabs and C the beams supporting the same. It is common practice to reenforce both the slabs and the beams. The rods employed are indicated at D and E.

In actual practice, when it is desired to erect a floor such as shown in Fig. 5, it is first necessary to construct the molds indicated at F. When these have been erected, short sections of supporting bars or strip material, such as shown in Fig. 1, are placed in the bottom of the beams as indicated at 6 in Fig. 5. The reenforcing rods are then laid on top of the bars and they are suitably spaced apart. The rods are then struck by a hammer or any other suitable implement, 20 and when so struck they crush down the teeth 2, as shown at 7 in Figs. 1 and 2. Seats are thus formed for the rods, the solid portion of the support holding them in the proper relation to the forms and the 25 wedging action of the crushed teeth preventing the rods from being easily displaced. They will thus be positively held in position and no amount of tamping or rough handling will displace them while the concrete is being poured into place.

The reenforcing rods indicated at D are next placed in position and they are spaced with relation to the forms supporting the floor slabs by interposing the supporting 30 bars as indicated at 8. All the rods are supported in a similar manner and a proper spacing is thus maintained between the forms and the rods, thus insuring proper positioning and proper bonding of the rods when 35 the concrete is poured and set. It might further be stated that the reenforcing bar support here illustrated is universally adaptable. It may be manufactured in long strips, which may be bent as shown in Figs. 40 45 3 and 4, or otherwise, or the strips may be cut and bent on the site where the building is being erected. For instance, hundreds of 50 short sections of reenforcing bar supports may be cut to proper length to fit the bottom of the floor beams indicated at C. Longer sections may be cut to support the rods D and so on. Such handling of material in great quantities promotes economy by sav-

ing time and labor and thus does not only decrease the cost of construction, but also 55 insures better workmanship and final strength, as far as the structure is concerned.

It will also be noted that the spacing of the reenforcing bars may be increased or decreased as desired, as it is only necessary to place the bars on top of the teeth 2 and then to crush the teeth wherever the bars are to be seated by merely striking the bars with a heavy hammer or the like. Any spacing may thus be obtained and any 65 size or diameter of rod may be employed without changing the size of the reenforcing bar support or otherwise changing the same.

While certain features of the present invention are more or less specifically illustrated, I wish it understood that various changes in form and proportion may be resorted to within the scope of the appended claims. I similarly wish it understood that the materials and finish of the 75 several parts employed may be such as the experience and judgment of the manufacturer may dictate or various uses may demand.

Having thus described my invention, what 80 I claim and desire to secure by Letters Patent is—

1. A reenforcing bar support of the character described comprising an elongated strip of metal adapted to stand on edge, and 85 a plurality of closely spaced, easily bendable teeth formed in one edge thereof.

2. A reenforcing bar support of the character described comprising a elongated strip, which is corrugated throughout its 90 length to permit it to be supported edgewise, and a plurality of closely interspaced easily bendable teeth formed in one edge thereof.

3. A reinforced concrete structure comprising a plurality of elongated supporting 95 members adapted to stand on one edge, a plurality of reenforcing rods adapted to be supported by said elongated members and disposed transversely of said members, and a plurality of closely spaced teeth or tines 100 formed in the upper edge of each elongated member, said teeth being easily crushed or bent to form seats for the reenforcing rods and to retain the rods against accidental removal.

HORACE M. WOOLLEY, JR.
